UNITED STATES PATENT OFFICE

HANS MUNSCH, OF KLEIN-GLIENICKE, NEAR POTSDAM, GERMANY, ASSIGNOR TO THE FIRM: IDEAL WERKE AKTIENGESELLSCHAFT FÜR DRAHTLOSE TELEPHONIE, OF BERLIN, GERMANY

LOUD-SPEAKER

Application filed October 22, 1928, Serial No. 314,185, and in Germany April 4, 1928.

This invention relates to loud speakers of the kind having an armature which floats, as in the known telegraph relays, in a magnetically neutral position between two pairs of 5 magnetic poles and which oscillates around a central pivot, under the influence of the speech currents. In such loud speakers it has not hitherto been possible easily to adjust the position of the armature between 10 the magnetic poles by means of an adjusting screw during the operation. This problem is solved by the present invention with comparatively simple means.

Figures 1-5 of the accompanying drawings illustrate the means for the adjustment of the armature between the ends of the pole shoes of the magnet.

Fig. 1 is a side elevation,

Fig. 2 is a plan view, whilst

20 Figs. 3, 4 and 5 illustrate the device in section.

For the sake of clearness, the steel magnet and its pole shoes, as well as the coils, in the middle hollow space of which the armature 25 oscillates, have not been shown in Figs. 1-5.

Fig. 6 shows the pole shoes provided on the end surfaces of the two limbs of the U-shaped magnet in conjunction with the coils but the armature adjusting means shown in 30 Figs. 1-5 are not indicated therein.

Fig. 7 illustrates the arrangement shown in Fig. 6 with the armature adjusting means shown in Figs. 1-5 screwed on to the pole shoes.

25 Figs. 8 and 9 show in two different elevations the armature adjusting device according to Figs. 1-5 assembled together with the steel magnets, the pole shoes and the coils.

As can be seen from Figs. 1-5, the armature *a* is carried by a thin, flat spring *b* through the middle of which it passes and to which it is soldered. The pin *s* for the diaphragm of the loud speaker is secured to one of the ends of the armature *a*. The 40 flat spring *b* allows the armature *a* to oscillate between the end surfaces of the pole shoes *p* secured to the ends of the limbs of the magnet *y*. (Figs. 6, 7, 8, 9). The directions in which the oscillations take place 45 are indicated by small arrows in Fig. 4.

As will be seen from Figs. 6 and 7, the pole shoes *p* are forked so that a free hollow space is left between them in which the coils *z* are accommodated. The outer flanges of the said coils *z* are provided with small projections *j* by means of which they are secured to the pole shoes. The armature *a* passes through the central hollow space of the coil *z* and a rectangular slit *o* is provided between the abutting flanges of the coils 55 through which slit the flat spring *b* passes freely. The latter spring is carried by a support *c* which may for instance consist of a massive piece of brass having a number of incisions *k*. The support itself is secured by means of two screws *d* (Fig. 3) to a frame-like base-plate *g*, preferably made by die-casting and which is formed with an upward gate-like projection *t*. The latter projection 60 serves for securing the pole shoes *p* to the ends of the limbs of the steel magnet *y*, as can be clearly seen in Figs. 7 and 8.

The base-plate *g* abuts, as can be seen from Figs. 8 and 9, against the side surfaces of 65 the limbs of the magnet *y* and by means of a counter-plate *q* lying against the opposite side of the magnet as well as by means of long screws *e* engaging in the base-plate *g*, the latter is firmly pressed against the steel magnet and is thereby secured in a fixed position to the magnet.

The central part of the support *c* (see Figs. 1-5) can resiliently rock around the points *x*-*x* owing to its incisions *k*. The rotary axis thus formed is in alignment with 75 the rotary axis of the armature. When the support is turned around its axis, the armature which it supports is taken along therewith, whereby it receives the desired adjustment. This turning movement, and thus the 80 adjustment of the armature, is effected by the adjusting screw *h* (Figs. 4, 7, 8) which, when turned to the right causes the support *c* to be pulled to the right against the pressure 85 of the spring *f*. The spring is supported against the metal plate *i* which is secured in a recess provided in the base-plate *g*. For the sake of clearness, the metal piece *i* is 90 not shown in Fig. 1 but is indicated in Fig. 4. In order to limit the rotation of the ad 95

justing screw *h* and consequently the adjustment of the armature, the former is provided with a pin *m* (Fig. 4) projecting on two sides, which pin abuts against the pin *n* provided on the metal piece *i*, thereby limiting the rotation of the adjusting screw to an angle of less than 180°.

It is also possible to render the construction of the support *c* carrying the armature mounting *b* from a metal casting, for instance, die-casting, which is not extensible or is only very little extensible, without the elastic rotation of the support being in any way affected at the weakened points *x*, around which it is intended to be elastically rotatable.

According to the invention, this is attained by this that suitably formed small plates or pieces of elastic metal, such as phosphor bronze, brass or the like, are inserted in the mould serving for the casting of the support *c* at the points where the weakenings in question are to be produced, which plates, during the casting or skirting of the metal into the mould, become firmly united therewith at the points where the metal comes into contact therewith, so that the completely cast support has weakened points which allow it to bend in the extension of the armature spring *b* without there being any danger of breakage.

In this way it is possible to simplify the manufacture of the support and at the same time cheapen the same.

35 What I claim is:—

1. A loud speaker having a magnetically neutral armature capable of turning around its central axis, a spring on which the said armature is mounted, a support to which the said spring is attached, the said support being capable of elastically turning around an axis which is in alignment with the central axis of the armature, and an adjusting screw for the said support, for the purpose of allowing the armature to be adjusted between the magnetic poles.
2. A loud speaker as claimed in claim 1, and in which the support consists of a single piece of metal weakened by incisions therein to such an extent that the said piece of metal is capable of slightly elastically turning around the incisions.

In testimony whereof I affix my signature.

55 HANS MUNSCH.
